UNITED STATES PATENT OFFICE.

EDWARD PARKINSON, OF PHILADELPHIA, PENNSYLVANIA.

KNITTING-MACHINE.

SPECIFICATION forming part of Letters Patent No. 739,708, dated September 22, 1903.

Application filed March 22, 1902, Serial No. 99,402. (No model.)

To all whom it may concern:

Be it known that I, EDWARD PARKINSON, a subject of the King of Great Britain and Ireland, and a resident of the city and county of Philadelphia, State of Pennsylvania, have invented certain new and useful Improvements in Knitting-Machines, of which the following is a specification.

My invention relates to improvements in knitting-machines, and more particularly to improvements in single-plate straight-knitting machines, the object of my invention being to furnish, first, a straight-knitting machine the capacity of which will be in a given time substantially double that of the ordinary straight single-plate machine; second, to furnish a knitting-machine with means whereby two threads will be successively engaged by the needles to form a fabric in different colors in either a plain stitch, in a tuck-stitch, in a cross-stitch, or in any combination desired of these stitches; third, to furnish means for the convenient and rapid substitution of different-colored threads for any particular thread being operated upon; fourth, to furnish improved and positive means for lifting and closing the latches of the needles; fifth, to furnish improved and positive means for opening the needle-latches; and, sixth, to furnish certain other improvements in this class of machine, which will be hereinafter fully described.

In the accompanying drawings, forming part of this specification, and in which similar characters of reference indicate similar parts throughout the several views, Figure 1 is a plan of my improved knitting-machine; Fig. 2, a front elevation of Fig. 1; Fig. 3, a front elevation, and Fig. 4 a side elevation, of the front thread-carrier; Fig. 5, a front, and Fig. 6 a side, elevation of the rear thread-carrier; Fig. 7, a plan of the needle-bed and needles; Fig. 8, a section of Fig. 7 on line 8-8; Fig. 9, a side elevation of the long, and Fig. 10 a side elevation of the short, needles; Fig. 11, a plan of the bottom of the cam-plate, showing the needle-operating cams; Fig. 12, a section of Fig. 11 on line 12-12; Fig. 13, a top plan of cam-plate; Fig. 14, a front elevation of Fig. 13; Fig. 15, a section of Fig. 13 on line 15-15; Fig. 16, a front elevation of the stops for limiting the movements of the thread-

carrier supports and of the means for carrying these stops; Fig. 17, a plan of Fig. 16; Fig. 18, a front, and Fig. 19 a side, elevation of the knives for positively opening the latches of the needles; Fig. 20, a side elevation of the device for holding the work against the outward thrust of the needles and the means for carrying the same; Fig. 21, a front, and Fig. 22 a side, elevation of the knife for closing the latches of the needles and preventing their ends from engaging the fabric; Fig. 23, a perspective view showing the needle-bed, needles, thread-carriers, and pressers or controllers for the needle-latches.

1 is the frame of the machine; 2, the cam race or guide, which forms part of or which may be bolted to the frame.

3 is the needle-bed, which is arranged at right angles to the cam-race. The needle-bed is furnished with a rearwardly-projecting tail 4, Figs. 7 and 8, to the outer end of which is pivoted one end of a lever 5, which is pivotally carried at 6, the other end of this lever being furnished with an operating-handle 7.

8 are set-screws carried by lever 5, one on each side of the fulcrum 6, which are adapted to engage the outer side of the cam-race or some other convenient fixed part to hold the lever 5 firmly in place. By loosening the screws 8 the lever 5 may be moved so as to move the needle-bed in or out to adjust the throw of the needles, or the outer end of the lever may be furnished with a spring *a*, Fig. 8-1, which will normally hold one of the stops 8 against its bearing, permitting the needle-race to be thrown in or out at will by rocking the lever 5 by the hand.

9, Figs. 1, 11, 12, 13, 14, is the cam-plate. In the drawings this plate is shown furnished with a pin 10, Figs. 1 and 2, to which is pivoted one end of a connecting-rod 11, the other end of which is pivoted at 12 to a crank 13, which is adapted to be turned by hand in order to reciprocate the cam-plate in the cam-race 2; but it will be understood that the cam-plate may be reciprocated in any other suitable and convenient manner either by hand or by power.

The cam-plate 9 carries upon its bottom two sets of cams 14 15, (best shown in Figs. 11 and 13,) which are similar in contour and one directly back of the other, the cam 14 being

adapted to operate the short needles 16 and the cam 15 the long needles 17. Each cam is a double one—that is, each cam as it is passed backward and forward across the needles and 5 fully opened is adapted to cause each needle during each single passage to make two complete movements or reciprocations.

The long and short needles may be placed side by side, first a long one, then a short 10 one, then a long one, and so on, or in any other desired way, and as the cams cause each needle to make two complete reciprocations for each single complete movement of the cam-plate and as the machine carries two threads 15 to the needles, as presently described, it is adapted to turn out in a given time double the work of these single-thread machines whose cams are single and cause but one reciprocation of the needles for each pass of the 20 cam-plate and which use but one thread at a time.

In order that I may form upon my machine a variety of stitches, I place at each end of each of the cams 14 15 latches 18 19 20 21, 25 which can be thrown so as to change the cams and vary the length of stitch. If the latches be thrown as shown in Fig. 11, for instance, the long needles operated by cam 15 will when the cam-plate is passed from right to 30 left first make a full stitch and then a full stitch, while the short needles actuated by cam 14 will first make a full stitch, which will be followed by a half or tuck stitch. On the return movement the operation will be reversed—that is, the long needles will first 35 make a full stitch and then a tuck-stitch, while the short needles will make first a full stitch and then a full stitch. It will be seen that other combinations will be formed by 40 throwing the latches so as to cut off or open the cams to form regular or tuck stitches at other intervals.

The latches are carried upon stems 22, which pass up through the cam-plate 9 and 45 which carry upon their upper ends arms 23 24, which are adapted to be engaged by stops 25 26, carried upon rods 27 28, carried by the top of the cam-plate 9. The rods 27 28 being moved back or forth will cause the stops 50 to engage such of the arms 23 24 as may be necessary to operate such latches as may be required to change the cams to vary the throw of the needles to form either a full or a tuck stitch.

55 The stems 22 are surrounded by coil-springs 29, Fig. 14, which always tend to normally throw the stems and latches so that the cams will be completely open—that is, to form full stitches. When the stops 25 26 60 engage the arms 23 24 to cause the latches to close off a certain portion of the cams, the ends of the arms being squared rest upon the flat tops of the stops, which prevents any movement of the latches during the engagement of the arms and stops.

65 It will be observed that I use the stitch-cams for forming the tuck-stitch instead

of the rising cams, as is usual. For certain kinds of work the stitch-cam could be made so that one side of it would operate 70 upon one pass of the cam-plate to cause the needles to form a tuck-stitch, while the other side of it would act upon the opposite pass of the cam-plate as a rising cam for the needles. In the drawings the stitch-cams are shown 75 fitted with latches 18 19 20 21, which permit a rapid change of the cams from full-stitch to tuck-stitch cams. It will be seen, however, that the latches may be omitted if the stitch-cams are required to form only tuck- 80 stitches.

30 31 are the thread-carriers, which are placed at the front of the machine, the latter to the rear of the former, as shown in Fig. 1. Both thread-carriers are adapted to be reciprocated horizontally across the face of the machine. They are both furnished with a perforated head 32, through which the thread passes, which is carried on the lower end of springs 33, which are furnished with slots 34, 90 through which pass set-screws 35, which pass into arms 36, which are secured to reciprocating slides or carriages.

39 is the reciprocating slide or carriage which carries the front thread-carrier; 38, a 95 rod or guide carried by the cam-plate 9, upon which slide 39 is carried and upon which it can slide.

37 is the reciprocating slide or carriage which carries the rear thread-carrier; 40, a rod 100 or guide carried by cam-plate 9, upon which slide 37 is carried and upon which it can slide.

The slides 39 37 are held frictionally upon their respective carrying-guides 38 40, but not 105 so tight but that they can be moved thereon, as presently described.

41 42, Fig. 1, are adjustable stops secured to rod or guide 40 by set-screws 43 or otherwise.

44 is a square-ended notch in the front of the carrying-slide 37.

45 46 are springs carrying at their inner or free ends stops 47 48, which are adapted to engage alternately with the notch 44 in slide 37. 115

49 50 are lifting-cams for stops 47 48, carried, respectively, by stops 41 42.

As has before been stated, the guide or slide 37, which carries the rear thread-guide, is held frictionally upon the rod 40, and under ordinary circumstances it would travel backward and forward with the cam-plate 9 and the rod 40, which is carried by the cam-plate. It is, in fact, so permitted to travel when it is desired to have in the fabric two 125 threads of the same color side by side; but if it be desired to have two colors alternating the guide or carrier 37 is arrested at a certain point in its travel to permit the front thread-carrier to pass it.

130 If the stops 47 48 are arranged to engage the notch in the slide 37 and the cam-plate 9 and connected parts are moving from right to left, the stops 50 will push the slide 37 in front of

it until the cam-plate reaches the end of its stroke, at which time the stop 47 drops into the notch 44. On the return stroke the stop 47, engaging the end of notch 44, holds the slide 37 still until the cam 49, passing in under stop 47, lifts it clear of the notch, at which time the stop 41 engages the left side of the slide 37 and moves it from left to right until the cam-plate 9 has reached the end of this stroke; when the stop 48 drops into notch 44 and holds the slide until the cam 50, carried by stop 42, comes along and lifts it out and the stop 42 carries the slide again to the left.

While the rear thread-guide is being intermittently reciprocated, as described above, the front thread-guide is also being reciprocated. It is carried, as before stated, by a sliding carrier 39, which is carried on a rod or guide 40, carried by the cam-plate 9.

51 52, Figs. 2 and 16, are stops carried by the frame of the machine.

53 54 are arms depending from carrier 39, which are adapted when the carrier is moved to the left or to the right to engage the stops 51 52 to arrest the movement of the carrier and thread-guide until the motion of the cam-plate is reversed, when the carrier is moved with it to the other end of the machine until it is stopped by the other stop—say 52—engaging the arm 54 and arresting the movement of the carrier 39 in this direction.

The stops for the carriers 37 39 are so arranged that at the ends of their strokes the front carrier 39 will be the first moved and it will continue to move until the front thread-guide has passed the rear one, when the rear guide will commence to move and they will be then moved together until they have both been moved completely across the front of the needle-race, when the front guide will be moved back, passing in front of the rear guide, after which this latter guide will commence to follow. This is the movement given the two guides when the threads carried by them are to be placed alternately.

45 It will be seen that if the front guide carries a white thread and the rear guide a black thread there will appear in the finished fabric first a white thread, next a black one, next a white one, next a black one, and so on, the white thread crossing over the black one at the end of each stroke of the machine.

It will be seen that by throwing the stops 47 48 and 51 52 into or out of action different combinations may be made.

Two white threads and one black thread may be made to appear in the finished fabric, two black threads and one white, two white and two black, and so on.

60 In working on a thick fabric, when the fingers of a glove are to be knitted to the hand, for instance, (it being understood that, as usual, the hand is first made upon a machine which knits this part only and is then transferred to the machine which knits the fingers,) it is necessary to provide means for preventing the ends of the latches from engaging

the fabric when the needles are drawn into the needle-bed, an accident that would spoil the fabric and break the needles. In order 70 to prevent accidents of this nature, I make use of a shield 55, Figs. 1, 2, 21, 22, and 23, which is placed just in advance of the forward end of the needle-bed and which engages the latches as the needles are drawn 75 into the bed, effectually preventing their ends from piercing the fabric and at the same time serving to positively close the latches.

As my machine is a straight-knitting machine, and as it is furnished with cams adapted to give to the needles two reciprocations for each single pass of the cam-plate—that is, two reciprocations upon each pass of the cam-plate to the left and two reciprocations upon each pass of the cam-plate to the right and 85 with two thread-carrier guides adapted to carry each a thread to the needles, the one always in advance of the other, and as I use but a single shield for the purposes above described, this shield has to be of such form as 90 to operate equally well when running backward or forward.

In order that the shield may operate upon the latches equally well upon either its forward or backward stroke, it has the same 95 form upon both its right and left sides, its form being particularly well shown in Fig. 23.

The shield 55 is carried frictionally upon a rod or bar 56, which is carried by and which reciprocates with the cam-plate and is adapted upon reaching the end of its strokes to be engaged by stops 74 75, Figs. 1, 2, 16, and 17, which are carried by the stationary frame of the machine. In the drawings these stops are shown formed by the inner ends of the 105 stationary plates 67, Figs. 16 and 17.

Supposing that the cam-plates are just commencing their stroke to the left, the shield 55 is in position to engage the latches of the needles as they are drawn inward, and as the 110 cam-plate is advanced to the left the rod 56, which frictionally carries the shield 55, is carried with it, the shield traveling with the front thread-carrier slide 39 and operating to engage the latches of the needles as these 115 latter are drawn inward by the first or left cam. Presently the first or left cam as it passes to the left passes away from the needles, and at this point the shield 55 is engaged by the stop 74 and comes to rest, the 120 rod 56 still moving with the cam-plate and sliding through its means of attachment to shield 55. As soon as the movement of the cam-plates is reversed and they commence to move to the right rod 56 commences to move 125 with them, and as the shield 55 is frictionally carried by this rod it moves with it and serves to engage the latches of the needles as they are moved inward by the right end of the now right-moving cams. It continues to move to 130 the right until that part of the cam which moves the needles inward passes away from them, when it is engaged and stopped by a stop 75, carried by the stationary part of the

frame, when it engages the latches upon the needles operated by the rear or left-hand end of the cam-plate, the movements of the machine being precisely the same upon each

5 stroke.

The hand of a glove is knitted upon one machine and the fingers upon another machine, the fabric knitted by the first machine being cut into suitable lengths and then

10 placed upon the needles of the second machine in order that the fingers may be knitted directly to the hand.

The danger of the latches of the needles piercing the fabric occurs during the first

15 pass of the cams after the hand portion has been placed upon the needles, as at this time there is an unusually thick mass of the fabric directly back of them. After the first pass of the cams the first course of the finger por-

20 tion is knitted to the hand portion, and there is no danger of the latches engaging the fabric. The thread will now close them, as usual.

This being the case the shield 55 is adapted to work in connection with the needles en-

25 gaging the thread carried by the front or forward thread-carrier. The needles engaging the thread carried by the rear or following thread-carrier have no shield to engage their latches, as it is unnecessary.

30 57 58, Figs. 1, 18, 19, 23, are latch-controlling guides carried by rods 38 40, which are carried by and reciprocate with the cam-plate, the lower ends of which as they are

35 reciprocated pass in front of the needles engage and hold the latches back against the needle-shanks. These latch-controllers have to be made so as to operate upon both their forward and backward movements.

The controller 57 engages the needles op-40 erated by the cams upon the left of the cam-plate, the controller 58 those operated by the cams upon the right of the cam-plate. Without these controllers the latches not infre-45 quently, owing to the rapid movements of the needles, close the hooks of the needles prematurely, causing miss-strokes.

The threads in passing from the lower ends of the thread-carriers pass down, under, and in contact with the under side of the hori-50 zontal portions of the controllers 57 58, as best shown in Fig. 23, and are thereby held in a position to insure their positive engagement by the hooks of the needles as these latter are drawn into the needle-bed.

55 In Fig. 23 the relative positions of the thread-carriers 30 31, the latch-controllers 57 58, and of the needles when the needle-actuating cams are moving to the left are shown. From this figure and Fig. 11 it will be seen

60 that on each pass of the cam-plate the needles are given two reciprocations, knitting two courses, one course being made by the thread carried by the front thread-carrier 30, the other by the thread carried by the rear

65 thread-carrier 31.

The latch-controllers 57 58 have an opera-70 tive side—that nearest the needle-bed—which

engages the latches of the needles, and an inoperative side—that facing away from the needle-bed. The threads in passing from the 75 lower ends of the thread-carriers engage the inoperative sides of the controllers 57 58, pass under these controllers and to the needles, the controllers holding the threads so that the hooks of the needles cannot miss engag- 75 ing them.

57 58, Figs. 1, 21, 22, are knife-blades carried by the rod 38, which upon their movements to and fro across the fronts of the needles pick up and positively lift or open their 80 latches, taking this duty from the threads and insuring perfect stitches for each needle.

The springs 45 46, carrying the stops 47 48, which serve to lock the slide 39, may be thrown out of action by the device best shown in 85 Figs. 16 and 17. In these figures the springs are shown carried upon a stationary plate 67, which is adapted to be bolted to the stationary frame of the machine.

68 is a sliding plate carrying a screw or 90 stop 69, which passes through a slot 70 in spring 45. By sliding plate 68 inward the spring 45 is depressed sufficiently to prevent the stop 47 engaging the notch in slide 37.

The outer thread-guide is furnished with 95 a dovetailed projection 71 on its back, which is adapted to be held in a corresponding slot in its carrying-standard 72. Hence this guide may be instantly lifted from place and another guide carrying a different-colored 100 thread may be as quickly put in its place. At the end of the machine, Figs. 1 and 2, I show holders 73 for carrying when not in use several thread-guides with different-colored threads. These guides may be removed from 105 the holders 73 and inserted in the carrying-standard 72 at any time when it is desired to place a different-colored thread in the fabric from the two originally used.

As has been stated, the heads 32 of the 110 thread-guides are carried upon springs 33. Should the front guide upon passing the rear one at the commencement of a stroke engage it, the springs carrying heads will yield and prevent breakage.

115 The needles travel in the usual guides in the needle-race 3, which is furnished with a transverse bar *c*, Figs. 7 and 8, under which they pass. They also pass under a bar *d* at the front of the race, these two bars insuring 120 their movement in a plane in the direction of their length. The ordinary construction of the long needles permits their use without change; but I furnish the short needles with a rearwardly-extending projection *e* to pass 12 under the bar *c*.

f, Figs. 1, 2, and 7, is a fly-wheel attached to or forming part of crank 13 or its carrying-shaft to equalize the motion of the crank, the connecting-rod 11, the cam-plate 9, and 130 connected parts.

In Figs. 1, 11, 12, 13, 14, and 15 it will be observed that the centers *j k* of the cams 14 15, which centers are projecting or rising

cams, are secured to the cam-plate 9 by means of screws *g*, which pass up through slots *h* in plate 9, said screws carrying thumb-nuts *i*, which when set down lock the centers to the plate. By loosening the thumb-nuts the centers of the cams may be moved in or out to cause the needles to make a tuck or half stitch at this point. Supposing the center part *j* of the cam 14, Fig. 11, to be moved out, as shown by dotted lines, and the latch 19 of this cam to be closed, as also shown by dotted lines, and the latch 21 of the cam 15 to be opened, as also shown by dotted lines, and the cam-plate to be passed from left to right, the short needles will first make a tuck-stitch and then a full stitch. The long needles will make first a full stitch and then a tuck-stitch, and on the reverse movement the short needles will make first a tuck-stitch and then a full stitch, while the long needles will make first a full stitch and then a tuck-stitch.

By means of the movable latches and movable central parts of the cams different combinations of full and tuck stitches can be made, as desired.

Having thus described my invention, I claim as new and desire to secure by Letters Patent—

1. In a knitting-machine, a projecting-cam, and a stitch-cam, one side of which is adapted to act upon one pass of the cam-plate as a rising cam and the other side of which is, upon the opposite pass of the cam-plate, adapted to act as a tuck-stitch cam.

35 2. The combination in a single-plate straight-knitting machine, of two double cams placed one directly behind the other, a cam-plate carrying said cams, latches at the ends of said cams and means for throwing 40 said latches so as to shorten or lengthen said cams.

45 3. The combination in a single-plate straight-knitting machine, of two double cams placed one directly behind the other, a cam-plate carrying said cams, latches at each of the ends of said cams adapted in one position to shorten them, stems passing up through said cam-plate carrying said latches, arms carried by the upper ends of said stems, sliding rods carried by said cam-plate, and stops carried by said rods adapted upon their movement to engage and operate said arms to operate said latches to shorten or lengthen said cams.

55 4. The combination in a straight-knitting machine, of a reciprocating cam-carrying plate, needles operated by the cams carried by said plate, means for carrying said needles, a thread-carrier for carrying a thread to said 60 needles, means for carrying and means for reciprocating said cam-carrying plate, means for carrying and means for reciprocating said thread-carrier, a shield the opposite sides of which are similar, means to confine said shield to movements in a right line, said shield being adapted to prevent the latches of the needles, upon each stroke, from engaging a fab-

ric carried by the needles, and means for carrying and means for reciprocating said shield back and forth across and above said needles. 70

5. The combination in a straight-knitting machine of cams adapted upon each pass to give the needles two reciprocations, the needles, two thread-carriers, one adapted to carry a thread upon each reciprocation of the cams 75 to the needles first actuated, and the other to carry a thread to the needles last actuated, means for carrying and means for reciprocating said cams, means for carrying and means for causing one of said thread-carriers upon both strokes of the machine to travel always in advance of the other, a shield adapted to prevent the latches of the needles upon both strokes of the cam-plate from engaging the 80 fabric carried by the needles, and means for carrying said shield in operative contact with the needles engaging the thread carried by the first moving thread-carrier.

6. The combination in a straight-knitting machine, of the needles, a cam-carrying plate 90 carrying cams adapted upon each pass of the cam-plate to give two reciprocations to each of said needles, a front and rear thread-carrier guide for carrying threads to said needles, arms carried by and reciprocating with 95 the cam-plate, and two latch-controllers, having operative and inoperative sides, carried by said arms, the operative side of said latch-controllers being adapted the one to hold open the latches of the needles operated by 100 one cam, the other to hold open the latches of the needles operated by the other cam upon both strokes of the cam-plate until just before the hooks of the needles engage the threads, and the inoperative sides to engage 105 the threads as they pass from the thread-carriers to cause them to pass under the controllers to the hooks of the needles.

7. The combination in a straight-knitting machine of cams adapted upon each pass to 110 give the needles two reciprocations, the needles, two thread-carriers, one adapted to carry a thread upon each reciprocation of the cams to the needles first actuated and the other to carry a thread to the needles last actuated, 115 means for carrying and means for reciprocating said cams, means for carrying and means for reciprocating said thread-carriers so that one, as the forward, upon both strokes of the machine, will always travel in advance of the 120 other, a shield adapted upon both strokes of the machine to prevent the latches of the needles which operate upon the thread carried by the first thread-carrier from engaging a fabric carried by the needles, a rod, reciprocating with the cams, upon which said shield is frictionally carried, and stationary stops for limiting the reciprocating movement of 125 said shield.

8. The combination in a knitting-machine, 130 of the needles, a cam-plate carrying cams adapted to reciprocate said needles, a thread-carrier guide for carrying a thread to said needles, and a latch-controller reciprocating with

said cam - plate and placed between said thread-carrier and needles, and over the latter, the outer side of said controller engaging the thread and directing it to the hooks of the 5 needles upon its under side.

9. Means for operating the needles of a knitting-machine comprising, in combination, a cam-plate, a central and end cams carried by said plate, and latches for altering the effective length of said end cams.

10. The combination in a knitting-machine of the needles, the operating-cams, the cam-plate and means for driving the latter, of two rods or guides, one placed to the rear of the 15 other, carried by said cam-plate, a slide or carriage carried upon each of said rods or guides, adjustable stops carried by said rods or guides adapted to alternately engage the opposite ends of said slides or carriages, adjustable stops, carried by the stationary frame of the machine, adapted to engage and hold said inner carriage at the end of each of its strokes, cams carried by the inner rod or guide adapted to engage and lift said adjustable stops from engagement with said 20 25

carriage, means whereby said cams may be thrown into or out of operative position, stops carried by the frame of the machine for limiting the travel of the carriage carried by the front rod or guide, means for throwing said 30 latter stops into or out of operative position, and spring-carried thread-guides carried by said carriages.

11. The combination with a knitting-machine furnished with a row of long and short 35 needles placed alternately side by side and means for carrying two threads simultaneously to said needles, of two double cams placed one directly back of the other, one cam adapted to operate the long and the other 40 cam adapted to operate the short needles, movable centers in said cams and movable latches at the ends of said cams whereby they may be adjusted so as to cause said needles to make either full or tuck stitches.

EDWARD PARKINSON.
